W. G. SCHRÖDER.
DEVICE FOR MIXING EMULSIONS.
APPLICATION FILED JULY 23, 1913.

Patented May 19, 1914.

UNITED STATES PATENT OFFICE.

WILHELM GOTTHILF SCHRÖDER, OF LÜBECK, GERMANY.

DEVICE FOR MIXING EMULSIONS.

1,097,474.

Specification of Letters Patent. Patented May 19, 1914.

Application filed July 23, 1913. Serial No. 780,805.

To all whom it may concern:

Be it known that I, WILHELM GOTTHILF SCHRÖDER, manufacturer, a citizen of the free town of Lübeck, in the Empire of Germany, and resident of 41 Luisenstrasse, in the said city of Lübeck, Germany, have invented new and useful Improvements in or Relating to Devices for Mixing Emulsions, of which the following is a specification.

10 This invention relates to a device for mixing emulsions:

The invention relates more particularly to devices in which the mixing is effected by means of stepped cones, that is to say, the fluid to be ground, is pressed through the seat of a cone or of a valve which itself, in the same way as its seat, consists of single steps, as described in the U. S. Patent 1062554. In order to enable the size of the 20 slot or gap between the single steps of the cone to be regulated, a solid cone with several steps was hitherto used while the valve seats were adjustable relatively to each other. According to this invention, the cone is 25 formed of single sections adjustable relatively to each other, in such manner that each single part is adjustable relatively to the others, and in that way the size of the slot or gap can be adjusted independently. 30 This device makes it possible to regulate exactly the slots and therefore the activity in the single stages, and to grind the working surfaces accurately. Moreover, liquids or gases can be introduced between the 35 single steps during the operation. The invention relates both to devices in which this cone is stationary, and to devices in which it is rotated in any desired manner. This rotation can be effected either by providing 40 the cone in the known manner with helical screw-thread or blades on which the liquid to be ground acts as in a turbine, or the cone can be supported by a spindle which is guided outward and provided with a driving pulley by means of which it can be rotated. The single steps of the cone can have 45 straight or oblique surfaces. The liquid escaping from the surfaces preferably passes first into hollow spaces in which a mixing 50 of the liquid takes place, which also prevents the fine liquid jets from impinging direct against the metal surfaces and thus damaging it.

A device according to this invention is

illustrated by way of example in the accompanying drawing in which—

Figure 1 is a vertical section, Fig. 2 a section on the line A—B of Fig. 1, and Fig. 3 is a section on the line C—D of Fig. 1.

As shown in the drawing, the cone has 60 four working surfaces b^1 b^2 b^3 b^4 , and the casing has also a corresponding number of annular spaces e^1 e^2 e^3 e^4 . The cone pressed on with heavy pressure, consists according to this invention, of four sections d d^1 d^2 65 and d^3 screwed into each other. To that end, the upper end of each single cone section is provided with a screwthread m^1 m^2 m^3 with which it engages with the corresponding tapped thread of the superposed 70 cone section. The perforation of each cone carrying the tapped thread, is exactly cylindrical at n^1 n^2 and n^3 , so that the single cones can fit exactly into each other. In this apparatus any desired number of conical surfaces can be screwed into each other in the manner described. The several conical sections thus tightly screwed together form 75 practically one solid member. This member fits into the casing in such a manner that the working surfaces on the several conical sections coat with corresponding working surfaces located within the casing. The term "two coaxing members" as used 80 in the claims applies to those members carrying a series of working surfaces coaxing with a corresponding series of working surfaces carried by the other. The grinding in of the working surfaces of the cones is 85 effected by the single cone sections being first screwed together and turned as a whole in such a manner that they correspond as accurately as possible to the corresponding working surfaces of the casing. The absolutely accurate grinding in then takes place, 90 so that during the grinding process all the working surfaces grind simultaneously. When the grinding process is completed, the cone is removed, divided into its single sections, and the distance of the single working 95 surfaces or the size of the slots α^1 α^2 α^3 is determined by inserting thin plates p so that when the cone is again introduced into the casing the bottom slot α^1 is slightly larger than the next α^2 , and the latter again 100 slightly larger than the next α^3 and so on.

In the construction illustrated, the casing is provided in addition to the inlet conduit

a, with two further inlet branches *a*¹ and *a*², the former of which opens into the hollow chamber *e*², and the latter into the hollow chamber *e*³. These inlet branches make it possible to supply to the emulsion to be treated, certain ingredients such as gases, liquids or even solid substances, for instance, those acting as catalysts, when it is desired to impart to the fats treated special properties, for instance higher melting points or the like. When liquid is introduced through the branches in question, the slots *a*¹ *a*² *a*³, etc., are of course adjusted in such manner that the increase of liquid or other substance should be also taken into account, so that approximately the same work of emulsioneing is performed at each working stage.

The cone is guided in the casing by making its bottom end triangular as shown in Fig. 3. The edges of the triangle are however turned cylindrically, so that they have proper guidance in the inlet pipe *a*. The uppermost cone *d*³ is provided at the circumference with grooves *o* and for the rest turned to suit exactly the inner wall of the casing, so that the liquid can escape only through the grooves *o*. In any case, the cone can also rotate, and to that purpose to be driven positively from the outside, or rotated by the liquid itself.

Having now particularly described and ascertained the nature of my said invention and in what manner the same is to be performed, I declare that what I claim is:—

1. In a device for mixing emulsions, the combination of two coacting members, means for introducing and discharging liquid, means for introducing matter at a plurality of points between said coacting members, and means for independently adjusting and setting the said members.

2. In a device for mixing emulsions, the combination of two coacting members, one of said members being provided with annular grooves adjacent to the working surfaces, means for introducing and discharging liquid, means for introducing matter at a plurality of points between said coacting members, and means for independently adjusting and setting the said members.

3. In a device for mixing emulsions, the combination of two coacting members, guide

means for holding the two in alinement, means for introducing and discharging fluid, and means for introducing matter at a plurality of points between said coacting members.

4. In a device for mixing emulsions, the combination of two coacting members, one of said members being provided with annular grooves adjacent to the working surfaces, means for introducing and discharging fluid, and means for introducing matter at a plurality of points between said coacting members.

5. In a device for mixing emulsions, the combination of a member carrying a V-shaped opening, stepped working surfaces within said opening, a second member, V-shaped, carrying working surfaces adapted to coact with first-mentioned working surfaces, said second member being formed of a series of units, each unit carrying a working surface, externally threaded at its upper portion and internally threaded at its lower portion, each unit adapted to screw into the unit above it and to receive the upper portion of the unit below it.

6. In a device for mixing emulsions, the combination of a member carrying a V-shaped opening, stepped working surfaces within said opening, a second member, V-shaped, carrying working surfaces adapted to coact with first-mentioned working surfaces, said second member being formed of a series of units, each unit carrying a working surface, externally threaded at its upper portion and internally threaded at its lower portion, each unit adapted to screw into the unit above it and to receive the upper portion of the unit below it, and means for regulating the distances between said working surfaces, comprising a plurality of disks, adapted to limit the distance that one unit is screwed into the one above it.

In testimony, that I claim the foregoing as my invention, I have signed my name in presence of two witnesses, this twelfth day of July 1913.

WILHELM GOTTHILF SCHRÖDER.

Witnesses:

JOHN WULF,
GERHARD ROSUNER.
